WELL TUBING

Charles W. Sproull, Houston, Tex.; Edith M. Sproull executrix of said Charles W. Sproull, deceased

Application March 11, 1946, Serial No. 653,595

6 Claims. (CL 285—22)

1

This invention relates to a well tubing and has more particular relation to a novel type of pump tubing.

An object of the invention is to provide a tubing of the character described having a by-pass conduit through which the gas in the well may escape to the ground surface independent of the tubing itself.

It is another object of the invention to provide a novel type of coupling for the tubing sections, said coupling having a by-pass therethrough.

A primary object of the present invention is to provide, in a well pump, a by-pass conduit leading from beneath the seal between the pump and the casing and having a discharge at the ground surface whereby gas collecting above the well fluid may be relieved from the well so that it will not collect and interfere with the operation of the pump.

Other objects and advantages of the invention will be apparent from the following specification which are illustrated by the accompanying drawings, wherein—

Figure 1 is a sectional view of a joint connecting the sections of a well tubing including the novel type of coupling.

Figure 2 is a side view thereof partly in section taken at right angles to the view shown in Figure 1.

Figure 3 is a cross-sectional view taken on the line 3—3 of Figure 1.

Figure 4 is a vertical, sectional view of the upper portion of a well casing with a well pump therein illustrating the invention.

Figure 5 is a side elevation, partly in section, of an intermediate section thereof; and

Figure 6 is a vertical, sectional view of the lower end thereof.

Referring now more particularly to the drawings wherein like numerals of reference designate the same parts in each of the figures, the numeral 1 designates a well casing to the upper end of which the casing head 2 is connected which is provided with an outlet line 3. Within the casing there is shown, in the present illustration, a pump tubing 4 which is sealed with the casing head by means of a cap 5.

The numeral 6 designates a pump cylinder whose lower end is equipped with the upwardly opening inlet valve mechanism 7. In the cylinder 6 there is a reciprocable plunger 8 which is reciprocated by the plunger rod 9. This rod in turn is reciprocated by a suitable pump operating mechanism which is enclosed in the casing 10 which is connected to the lower end of the pump tubing 4.

2

In the present illustration a fluid lift type of pump is shown and beneath the casing 10 there is a packing assembly 11 forming a seal between the upper end of the pump cylinder and the casing 1.

The lower end of the pump cylinder is submerged in the liquid, in the casing 1, to be pumped and in oil wells gas accumulates between the packing assembly 11 and the surface of the liquid and if allowed to continue to accumulate it will eventually enter the pump cylinder and interfere with the operation of the pump.

As hereinabove indicated it is one of the chief objects of the invention to provide means for relieving the gas which accumulates in the well. In order to do this the gas must be by-passed from the casing beneath the packing assembly and discharged at the ground surface.

A special type of pump tubing has, accordingly, been designed which will now be described.

This pump tubing is composed of substantially similar tubular sections 12 whose adjacent ends are united by a special type of coupling 13. This coupling is internally threaded at each end and also has the internal annular channels 14, 14 which are connected by a vertical channel 15 in the coupling. This channel 15 is preferably formed by externally grooving the coupling 13 longitudinally from one channel 14 to the other and then welding a plate, as 16, over the groove.

There are the inside tubular upper and lower elbows 17, 18 associated with each coupling. One end of each elbow is fitted through an opening in the coupling which communicates with the corresponding channel 14 and the outer ends of the elbows are then welded to the coupling, to secure the elbows in place and said welded outer ends are threaded so as to match the external threads of the adjacent ends of the tubing sections 12 so that the ends of the coupling 13 can be threaded onto the adjacent ends of the sections 12.

The inner end of the elbow 17 is turned upwardly and the inner end of the elbow 18 is turned downwardly so that said elbows will receive the adjacent ends of a pipe 19.

From the foregoing it will be apparent that each section of the pump tubing with the corresponding by-pass pipe 19 and elbows 17, 18 constitute a unit to the end that the pump tubing may be made up of these pre-assembled units. The pump tubing may therefore be conveniently made up while installing the pump in the well and broken up when it is desired to pull the pump.

55 It is to be noted, however, that the lower coupling

13 has its lower elbow 17a on the outside rather than on the inside with the upper end of the pipe 19a connected into said elbow 17a. This pipe 19a leads down through the packer assembly 11 and terminates in the gas collecting chamber beneath.

The upper end of the by-pass pipe, which is made up of the pipe sections 19, and 19a, is turned laterally through the pump tubing, above the casing head and is equipped with a control valve 20.

From the foregoing it is apparent that the gas collected above the oil, and beneath the pump packing in an oil well may be released, at the will of the operator, so as not to interfere with the operation of the pump.

The drawings and description are illustrative merely while the broad principle of the invention will be defined by the appended claims.

What I claim is:

1. In a tubing having tubular sections, a one piece tubular coupling connecting said sections and having a single channel within the wall thereof whose ends terminate within the tubing and tubular fittings in the tubing connected into the channel ends.

2. In a tubing having tubular sections, a tubular coupling connecting said sections and having a channel within the wall thereof whose ends terminate within the tubing, independent pipes in the respective sections and tubular fittings which connect the adjacent ends of said pipes into the corresponding ends of the channel.

3. In a well tubing composed of tubular sections and tubular couplings into which the adjacent ends of the sections are threaded, an independent pipe within each section and adjacent the inside wall thereof, a tubular elbow at each end of each section and anchored thereto and into which the corresponding ends of the pipe in

said section are connected, each coupling having a single, longitudinal channel within the wall thereof whose ends are in communication with the passageways through the corresponding elbows.

4. In a well tubing, a tubular tubing section whose ends are externally threaded, an independent pipe in said section whose ends terminate in tubular elbows which extend outwardly through, and are anchored to, said threaded ends.

5. In a well tubing, tubular tubing sections whose ends are externally threaded, a tubular coupling threaded onto, and connecting, adjacent ends of said sections and having a single channel in the wall thereof extending longitudinally of the coupling, an independent pipe in each tubing section, each pipe terminating in a tubular elbow which extends through and is anchored to, the corresponding threaded end of the section and communicates with said channel, whereby a continuous conduit is formed through said pipes and channel.

6. The combination with a well casing and a tubing therein leading to the ground surface of annular packing between the tubing and casing and an independent conduit whose lower end is extended through said seal and whose upper end extends to the ground surface, said conduit including by-pass channels through the tubing couplings.

CHARLES W. SPROULL.
